(57) **CLAIM**

The ornamental design for a remote control car toy, as shown and described.

DESCRIPTION

FIG. 1 is a perspective view of a remote control car toy showing my new design;

FIG. 2 is another perspective view thereof;

FIG. 3 is another perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof; and,

FIG. 10 is an enlarged partial view taken from a rear wheel shown in FIG. 1.

The dash-dash broken lines in the drawings depict portions of the remote control car toy that form no part of the claimed design. The dot-dash-dot broken lines in the drawings depict boundaries of the enlarged area shown in FIG. 10 and form no part of the claimed design.
